UNITED STATES PATENT OFFICE

KARL NAST, OF STUTTGART, GERMANY

RAIL JOINT

Application filed January 28, 1932, Serial No. 589,341, and in Germany July 8, 1931.

My invention relates to rail joints and more particularly to means for filling in the gap at the joint. It is an object of my invention to fill in the gap in such manner that shocks are avoided.

To this end I provide filling plates for the gap and means for varying the number of plates in the gap in conformity with its width. The filling plates may for instance be partly housed in the gap and partly in a recess of one rail and the means for varying the number of plates in the gap may be connected to the other rail. I may provide a partly horizontal and partly inclined race in the recess along which the plates are moved by the means connected to the other rail.

By these means the gap is kept filled and variations in the size of the gap are automatically made up for by plates being fed into the gap or returned into the recess, according to temperature conditions.

Gaps at the rail joints are inevitable in order to make up for the heat expansion of the rails but are most undesirable not only because the shocks are unpleasant to the passengers but also because they bring about considerable wear of the rails and the rolling stock. It has frequently been attempted to fill in or to bridge the gaps, for instance, by lateral impact or easing rails, but these expedients have failed because they are without means for providing for the variations in the size of the gap and for effecting a complete and unbroken gap filler.

The drawbacks of the means which have already been suggested, are eliminated according to my invention, as under the influence of the means connected to one of the rails the filling plates in the recess of the other rail are moved into and out of the gap as required by the variations in the size of the gap, and there will never be any clearance at the gap.

The friction between the filling plates must not be excessive because it must not interfere with the free relative displacement of the plates as they move into and out of the gap. Preferably the faces of the plates are ground or polished so as to present a minimum of friction and in order to facilitate the sliding

movement of the plates in the recess their upper and lower edges are preferably rounded. On the other hand, strength is an important item as the plates have to stand the load of the wheels, and therefore they are preferably made of high-class steel. When the plates are under the load of a wheel they are pressed together so tightly that relative displacement is prevented and the plates form a solid unit with the rails which stands all stresses.

A particular advantage of my novel joint is that, in view of the complete filling of the gaps at the joints the gaps may be very large and therefore it is possible to weld several lengths of rails into a section, with gaps only at the ends of the welded section. Thus, rails may be welded together to a length exceeding half a mile, and provided with gaps and fillers according to my invention only at both ends of the section. By these means the number of gaps per unit of length is reduced to a minimum.

In the drawings affixed to this specification and forming part thereof, various rail joints embodying my invention are illustrated diagrammatically by way of example.

In the drawings

Fig. 1 is a partly sectional elevation,

Fig. 2 is a complete elevation,

Fig. 3 is a section on the line III—III of Fig. 2,

Fig. 4 is a section on the line IV—IV in Fig. 2, of a rail joint in which the races for the filling plates are constituted by a recess in one of the rails,

Fig. 5 is a perspective illustration of a joint in which the races are constituted by a combined race block and fish plate in the recess of the rail,

Fig. 6 is a plan view of Fig. 5,

Fig. 7 is an elevation of the recessed rail end in which the race block is fitted,

Fig. 8 is a perspective illustration of the race block,

Fig. 9 is an elevation of one of the filling plates,

Fig. 10 is a perspective illustration of a fitting for bridging a portion of the gap,

Fig. 11 is a perspective illustration of the

block by which the filling plates are controlled, and a portion of the race block,

Fig. 12 is an elevation of a joint having means for exerting extra pressure on the plate-control block,

Fig. 13 is a plan view of a skew joint according to my invention,

Fig. 14 is a section on the line XIV—XIV in Fig. 13,

Fig. 15 is a perspective illustration of a filling plate,

Fig. 16 is a perspective illustration of the plate-control block and a portion of the bearing block,

Fig. 17 is a perspective illustration of a fitting, all for the skew joint, and

Fig. 18 is a diagram showing a portion of a track equipped with my novel joint.

Referring now to the drawings, and first to Figs. 1 to 4, I and II are the rails at opposite sides of a gap to be filled in with filling plates *a*, *b* is a recess or slot in the end of rail II, with an inclined race *b*₂ at the bottom, a face *b*₄ at the top which extends in parallel to the race *b*₂ and intersects the tread of the rail head at some distance from the end of the rail, and a horizontal race *g*₂ which adjoins the race *b*₂ at a point vertically below the shortened rail head. The end of rail I is squared and does not require machining. The plates *a* which are preferably rounded at their upper end and lower edges to facilitate their sliding on the races *b*₂ and *g*₂, are partly in the recess *b* on the inclined race *b*₂, and partly on the horizontal race. *v* is a fitting extending from the foremost plate *a* to the end of the other rail I which is cut square, so that the fitting *v* partly bridges the gap and, together with the plates *a*, fills in the gap which extends from the squared end of the rail I to the end of the rail head II at its intersection with the face *b*₄ of the recess. The fitting has lugs *v*₁, *v*₂ for welding it to the rail I, as shown for a modified fitting in Fig. 10. *c* is a control block for the plates *a* which slides in the recess *b* and bears on the innermost plate *a*. *e*₁, *e*₂ are links which are pivoted to the rail I at opposite sides of its web by pins *f*, bear on fish plates *z*, Fig. 2, and engage in slots *c*₃ in opposite faces of the control block *c* with, preferably dovetailed, lugs *e*₃. This, or some other kind of yielding connection, is required as the links, being restrained by the fish plates *z*, cannot rock as the block *c* moves on race *g*₂.

The arrows in Fig. 1 indicate the contraction of the rails in cold weather by which the gap becomes wider. The end of the rail I moves to the left and the end of the rail II moves to the right. The control block *c* moves to the left with the rail I to which it is connected at *f*, rises on the inclined race *b*₂ and moves more plates onto the horizontal race *g*₂ and into the gap. In

hot weather the ends of the rails move in opposite direction to the arrows in Fig. 1 and the gap becomes narrower. The control block *c* recedes on the race *b*₂ and plates *a* are forced onto the inclined race *b*₂ from the horizontal race *g*₂.

In view of the normal section of the rails, with their comparatively thin webs, the area presented to the plates *a* in the region of the web is very small at their faces as well as at their lower edges. This is unfavorable under all conditions because it increases the pressure per unit of area at the faces and the edges of the plates, and in particular it is undesirable to support the lower edges of the plates, with the heavy load of the wheels bearing on them, only by the narrow seat afforded by the web. In order to eliminate this drawback I provide means for presenting larger areas to the faces and lower edges of the plates. Such means may be the fish plates *z* at both sides of the web which are secured only to the rail II by screws *z*₁ or any other suitable means, and on which the filling plates *a* bear so that the added areas of the web section and the two fish plates are available for bearing the load on by the fillings *a*. The fish plates *z* are shaped in conformity with the races *d*₁ and *d*₂ of the recess *b*.

In order to present an area equal to the faces of the filling plate *a*, the fitting *v* is made as wide as the rail head throughout its depth, Fig. 4.

A more elaborate joint is illustrated in Figs. 5 to 11. Referring first to Fig. 7, the upper portion *b*₄ of the recess *b* in the rail II is arranged as described but its lower race is cut away with the exception of a short land *b*₁. The remaining portion of the web is cut away in parallel to the base and forms a ridge *g*₁ with holes *b*₃ therein. The fish plates *z* are replaced by projections *n*₁, *n*₂ at both sides of a race block *n*, Fig. 8, of channel section, which is placed on the ridge *g*₁ with its central recessed portion. The inner end of the race block is inclined at *b*₂ and its outer end is horizontal at *g*₂, similarly to the races in the recess *n*₃ are three holes in the sides of the race block *n* which are aligned with the holes *b*₃ in the ridge *g*₁ for the reception of the bolts *z*₁, Fig. 2. The holes *n*₃ are elongated so that the race block *n* may be adjusted on the ridge *g*₁ if required by repair or fitting operations. The upper end of the inclined race *g*₂ is again vertically below the point where the rail head intersects with face *b*₄. Obviously the inclination of the races *b*₂ and the face *b*₄ at the rail head which is parallel to the race *b*₂, may be varied but will not be influenced by considerations regarding the inevitable weakening to which the end of the rail II is subjected by the recess *b* because the pointed upper end of the rail head is supported throughout by the fill-

ing plates and the control block *c*. In view of its function as a supporting member for the undercut rail head, the control block *c* should be made long. The sides of the bearing block *n* are dovetailed at *n*₄, and *n*₅ are sectioned strips which are inserted in the dovetails at both sides of the horizontal race *g*₂. The filling plates *a*, Fig. 9, and the fitting *v*, Fig. 10, are dovetailed in conformity with the dovetail *n*₄. The fitting has the lugs *v*₁, *v*₂ for engaging below the rail head but is not welded to the rail I, and its sides are equipped with lugs *v*₇. The plates have lugs *a*₁ and *a*₂ at their bases, which at their inner faces are shaped in conformity with the dovetail *n*₄ and the strips *n*₅, the upper portion of the dovetails in the plates being vertical as shown at *a*₃ in Fig. 9 and only the lower portions being inclined as shown at *a*₄. The jibs *n*₅ which are detachable, being held by screws or the like, permit insertion of the fitting *v* and the plates *a* from above by extracting the strips longitudinally so that the fitting and the plates are readily exchangeable.

The detachable fitting *v* should be so designed that it can be extracted even if the width of the gap is at its minimum. To this end the fitting is divided as shown in Fig. 10 and equipped with an extension *v*₃ which is shouldered at *v*₄ to fit in notches of the fitting *v*. The thickness of the extension *v*₃ is so determined that after a few plates *a* have been removed, it can slide on the horizontal race *g*₂ until its shoulders *v*₄ are free of the fitting *v*. The strips *n*₅ are extracted and the fitting *v*, with the extension *v*₃, is lifted out of the gap. Obviously the thickness of the extension *v*₃ should at least be equal to the length of the lugs *v*₁, *v*₂ so that the head of rail I will not interfere with the upward extraction of fitting *v*.

Preferably, detachable lugs *o*, *o* are provided at opposite sides of the rail bases at the rails I, II for holding the race block *n* in position.

The plate-control block *c*, Fig. 11, is equipped with dovetailed lugs *c*₁ at both sides for engaging in the dovetails *n*₄ of the race block *n*, and is recessed for the reception of the web of rail II, its side plates *c*₂ bearing on opposite sides of the web. This makes up for the weakening of the rail II by the recess *b* as the side plates *c*₂ support the rail head which is undercut by face *b*₁, even if the gap is very large. *u* is a block at one side of the rail II which is provided for a purpose to be described, and *y* is a wedge inserted between the upper face of the block *u* and the lower face of the rail head, with its wedge face bearing on the corresponding side plate *c*₂ of the control block *c*, so as to reinforce the rail head and to assist in the guiding and supporting of the control block *c*. The wedge *y*

may be welded or otherwise secured to the side block *u* as shown in Fig. 5, or made integral with it, as shown in Fig. 12.

In the modification illustrated in Figs. 9 to 11, the links *e*₁, *e*₂ are supported on the dovetailed lugs *v*₇ at the sides of the fitting *v* and its extension *v*₃, and also on the lugs *a*₁, *a*₂ of those plates *a* which are on the horizontal race *g*₂ so that the links cannot rock about their pins *f* as the control block *c* slides on the race *g*₂.

In order to hold the faces of the filling plates *a* engaged still more tightly under the load of a wheel, supplementary compression means such as illustrated in Fig. 12 may be provided by which a portion of the load on the wheel is translated into a horizontal force acting on the control block *c*. A single pin *f* extends through the web of the rail I. At the side of the rail where the compression means is arranged (this depends on whether the tread or the flange of the tire operates the compression means) an arm *q* is secured on the pin *f*. *x* are eccentrics on both ends of the pin *f* (only one of which is shown in Fig. 12) and the links *e*₁, *e*₂ are mounted on the eccentrics. The link *e*₂ is extended beyond the lug *e*₃ with which it engages in the slot *c*₃ of the block *c*, and is pivotally connected to an arm *s* at its free end which extends in parallel to the arm *q* of the pin *f*. *r* is a rod connecting the free ends of the arms *q* and *s*. The portion of the parallelogram which extends beyond the lug *e*₃ is supported by the block *u*. Pivoted to the connection of *r* and *s* is an arm *t* which is inclined to the rails at the same angle as the arms *q* and *s* but extends in opposite direction, with its free end bearing on the block *u*. This arm *t* is provided for cooperation with wheels moving from the right to the left in Fig. 10, while the arm *q* is acted on by wheels moving from the left to the right. Obviously, in a track which is negotiated in one direction only, the arm *t* is dispensed with. Instead of being free to slide on the upper face of the block *u*, the arm *t* may be inserted in a slot (not shown) in the block, or a slotted guide above the block.

The parallelogram illustrated in Fig. 12 is adapted to be operated by the flanges of the tires and its top rod *r* is held in a given position with respect to the tread of the rail head, as determined by the width of the gap. When a wheel arrives from the left on rail I it forces down the arm *q* and rotates the pin *f*. The eccentrics *x* on the pin *f* pull the block *c* toward the plates *a* through the medium of links *e*₁ and *e*₂ so that in addition to the compression under the load of the wheel, the plates are held closely packed at their faces by the additional pressure acting on the control block *c* and will not be bulged or otherwise deformed.

The parallelogram has been shown considerably shortened for the sake of convenient illustration, but in fact it must be so long that its top rod r remains depressed while a train runs across the gap. This condition is fulfilled if the rod r is somewhat longer than the maximum distance of two wheels in the train.

In the butt joints which have been illustrated the load, assuming that the wheel arrives from the left, acts successively on the rail I, the fitting v , the plates a and the rail II. In order to provide a more gradual application of the load the skew joint illustrated in Figs. 13 to 17 may be provided. Only slight alterations in the described members are required for the skew point. Thus, the links e_1 and e_2 must obviously have different lengths.

Fig. 14 shows a somewhat modified fitting v . The fitting, in addition to the lower lugs v_7 on which the links e_1 , e_2 are supported, is equipped with an upper lug v_5 so that the links e_1 , e_2 are held in a groove. If the compression means according to Fig. 10 are provided, the links must have a corresponding play in their grooves but are restrained in upward direction by the lugs v_5 . Obviously the provision of such grooves is not limited to fittings for the skew joint.

Fig. 17 is a perspective illustration of the fitting v as shown in Fig. 14. This fitting is equipped with a tread v_6 which is flat at one end and arched at the other so that by this fitting rails having flat and arched heads may be connected.

In the skew joint there is a certain difficulty about the dovetails a_4 at the lugs of the filling plates a for the plates are machined with squared edges which on account of the inclination of the plates to the rail, make line contact only at the dovetails n_4 and at the strips n_5 of the race block n . In order to eliminate this difficulty, curved, for instance, semicircular, recesses a_5 are formed in the plates, and ribs n_6 of corresponding section are formed on the race block n as shown in Fig. 14. The provision of the ribs n_6 facilitates the sliding of the plates on the races. Obviously such ribs might also be provided as supplemental guiding means in butt joints although in butt joints they are not as important as in skew joints.

The joint illustrated in Fig. 13 is a bridge joint, with a supporting plate d . Supporting plates d are preferably provided under all conditions, not only for the bridge joint illustrated in Fig. 12, and not only for skew joints, in order to eliminate all tendency to relative displacement of the rails, and the shearing stresses resulting therefrom.

Referring now to Fig. 18, the rail section I may be built up from a considerable number of individual rails welded together, and, as mentioned, may be more than half a mile long. It is fixed only at its centre at B_1 so

that its ends are free to expand. Short rail sections are inserted between the long sections I. In the present instance, it has been assumed that the short sections are welded from two rails II of normal length, and fixed at the centre B_2 . w are the joints between the long and short sections which are filled in with plates a as described.

Fig. 18 shows four joints w for the connection of three long, and two short sections. It will be understood that by the arrangement illustrated the number of gaps and consequently the number of means for filling the gaps, is reduced to a minimum. Another advantage is that repair and other operation are much facilitated for it is only necessary in such cases to detach the short sections II-II at B_2 . However, it is also possible to provide exclusively long sections of rails welded together in combination with a single gap-filling device according to my invention between each two sections instead of the short sections II, II and the two gaps w , w which each requires.

When the joints are assembled all members in frictional contact should be amply lubricated, including the plates a . The plates, as mentioned, are preferably made of high class steel with faces ground to a fine polish. By lubricating the plates the friction is further reduced and striking by adhesion at the polished faces is prevented.

I wish it to be understood that I do not desire to be limited to the exact details of construction shown and described for obvious modifications will occur to a person skilled in the art.

In the claims affixed to this specification no selection of any particular modification of the invention is intended to the exclusion of other modifications thereof and the right to subsequently make claim to any modification not covered by these claims is expressly reserved.

I claim:

1. A rail joint comprising filling plates for the gap, and means for varying the number of plates in the gap in conformity with its width.

2. A rail joint comprising filling plates for the gap which are partly housed in the gap and partly in a recess of one rail, and means connected to the other rail for varying the number of plates in the gap in conformity with its width.

3. A rail joint comprising filling plates for the gap which are partly housed in the gap and partly in a recess of one rail, an inclined race in said recess, a horizontal race extending into said gap, and means connected to the other rail for varying in conformity with the width of the gap the number of plates which are on the horizontal race.

4. A rail joint comprising filling plates

- for the gap, means for varying the number of plates in the gap in conformity with its width, and a fitting inserted between said plates and one of said rails.
5. A rail joint comprising filling plates for the gap which are partly housed in the gap and partly in a recess of one rail, means connected to the other rail for varying the number of plates in the gap in conformity with its width, and a fitting connected to the other rail and arranged between the end of the other rail and the first plate in said gap.
10. A rail joint comprising filling plates for the gap which are partly housed in the gap and partly in a recess of one rail, means connected to the other rail for varying the number of plates in the gap in conformity with its width, and a fitting detachably connected to the other rail and arranged between the end of the other rail and the first plate in said gap.
15. A rail joint comprising filling plates for the gap which are partly housed in the gap and partly in a recess of one rail, means connected to the other rail for varying the number of plates in the gap in conformity with its width, and a fitting detachably connected to the other rail and arranged between the end of the other rail and the first plate in said gap.
20. A rail joint comprising filling plates for the gap which are partly housed in the gap and partly in a recess of one rail, means connected to the other rail for varying the number of plates in the gap in conformity with its width, and a fitting detachably connected to the other rail and arranged between the end of the other rail and the first plate in said gap.
25. A rail joint comprising filling plates for the gap which are partly housed in the gap and partly in a recess of one rail, means connected to the other rail for varying the number of plates in the gap in conformity with its width, and a fitting detachably connected to the other rail and arranged between the end of the other rail and the first plate in said gap, and a detachable extension at the outer end of said fitting connected thereto by a clutch, the lengths of said fitting, said extension and said clutch being so determined with respect to the minimum width of said gap that said extension and said fitting can be extracted from the gap.
30. A rail joint comprising filling plates for the gap, means for varying the number of plates in the gap in conformity with its width, and means for making up the web section of one of said rails into areas equal to the corresponding area of said plates.
35. A rail joint comprising filling plates for the gap, means for varying the number of plates in the gap in conformity with its width, and a fitting inserted between said plates and one of said rails, the area which said fitting presents to the plates being equal to the area of their faces.
40. A rail joint comprising filling plates for the gap which are partly housed in the gap and partly in a recess of one rail, means connected to the other rail for varying the number of plates in the gap in conformity with its width, and fish plates on opposite sides of the rail web and at the lower face of said recess for supporting the lower edges of said filling plates.
45. A rail joint comprising filling plates for the gap which are partly housed in the gap and partly in a recess of one rail, a race block inserted in said recess, for supporting the lower edges of said filling plates, and means connected to the other rail for vary-
- ing the number of plates in the gap in conformity with its width.
12. A rail joint comprising filling plates for the gap which are partly housed in the gap and partly in a recess of one rail, a race block inserted in said recess and recessed for the reception of the web of the first-mentioned rail for supporting the lower edges of said filling plates, and means connected to the other rail for varying the number of plates in the gap in conformity with its width.
13. A rail joint comprising filling plates for the gap which are partly housed in the gap and partly in a recess of one rail, a race block inserted in said recess for supporting the lower edges of said filling plates, projections at opposite sides of said race block for engaging the web of the other rail, and means connected to the other rail for varying the number of plates in the gap in conformity with its width.
14. A rail joint comprising filling plates for the gap which are partly housed in the gap and partly in a recess of one rail, a race block inserted in said recess for supporting the lower edges of said filling plates, guides at the sides of said race block which are so designed as to prevent upward movement of the members seated on said race block, and detachable strips inserted between said members and said guides to permit extraction of said members in upward direction, and means connected to the other rail for varying the number of plates in the gap in conformity with its width.
15. A rail joint comprising filling plates for the gap which are partly housed in the gap and partly in a recess of one rail, a plate-control block mounted to slide in said recess and to engage the inner face of the innermost filling plate, links pivoted to opposite sides of the other rail, and means at the free ends of said links for connecting said links to said block while permitting relative vertical displacement of said links and said block.
16. A rail joint comprising filling plates for the gap which are partly housed in the gap and partly in a recess of one rail, a plate-control block mounted to slide in said recess and to engage the inner face of the innermost filling plate, links pivoted to opposite sides of the other rail, and means at the free ends of said links for connecting said links to said block while permitting relative vertical displacement of said links and said block, the length of said control block being so determined that it is able to support the undercut portion of the rail head in said recess.
17. A rail joint comprising filling plates for the gap which are partly housed in the gap and partly in a recess of one rail, a plate-control block recessed for the reception of the web of the first-mentioned rail mounted to slide in said recess and to engage the

inner face of the innermost filling plate, links pivoted to opposite sides of the other rail, and means at the free ends of said links for connecting said links to said block while permitting relative vertical displacement of said links and said block.

18. A rail joint comprising filling plates for the gap, means for varying the number of plates in the gap in conformity with its width, and means controlled by the wheels of vehicles running on the rails for exerting additional pressure on said number-varying means.

19. A rail joint comprising filling plates for the gap, means for varying the number of plates in the gap in conformity with its width, a system of links and levers pivotally mounted on said rail in the form of a parallelogram, the link at the upper end of said parallelogram being adapted to be depressed by the wheels of vehicles running on the track.

20. A rail joint comprising filling plates for the gap which are partly housed in the gap and partly in a recess of one rail, a plate-control block mounted to slide in said recess and to engage the inner face of the innermost filling plate, a pin mounted to rotate in the other rail, eccentric means on both ends of said pin, links connected to said eccentric means at one end, means at the other ends of said links for connecting said links to said control block while permitting relative vertical displacement of said links and said block, and an arm on said pin which is adapted to be depressed by the wheels of the vehicles running on the rails so as to rock said pin.

In testimony whereof I affix my signature.
